CLAIM

The ornamental design for a plush toy animal, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a plush toy animal, showing our new design;

FIG. 2 is a right side view thereof;

FIG. 3 is left side view thereof; and,

FIG. 4 is a rear view thereof.
